US0D1010574S

(12) **United States Design Patent** (10) Patent No.: **US D1,010,574 S**
Chen et al. (45) Date of Patent: ** Jan. 9, 2024

(54) **EARPHONE CHARGING CASE**

(71) Applicant: **BEIJING XIAOMI MOBILE SOFTWARE CO., LTD.**, Beijing (CN)

(72) Inventors: **Weiwei Chen**, Beijing (CN); **Keliang Xun**, Beijing (CN); **Qing Li**, Beijing (CN); **Bokang Jiao**, Beijing (CN)

(73) Assignee: **BEIJING XIAOMI MOBILE SOFTWARE CO., LTD.**, Beijing (CN)

(**) Term: **15 Years**

(21) Appl. No.: **35/513,293**

(22) Filed: **Sep. 14, 2021**

(80) **Hague Agreement Data**

Int. Filing Date: **Sep. 14, 2021**

Int. Reg. No.: **DM/217968**

Int. Reg. Date: **Sep. 14, 2021**

Int. Reg. Pub. Date: **Dec. 31, 2021**

(30) **Foreign Application Priority Data**

Mar. 15, 2021 (CN) 202130138716.9

(51) LOC (14) Cl. **13-02**

(52) U.S. Cl.

USPC **D13/108**

(58) **Field of Classification Search**

USPC D13/108; D3/294, 274, 273; D14/223

CPC A45C 11/00
